Primary Examiner — Derrick E Holland(57) **CLAIM**

The ornamental design for an LED road flares arrow, as shown and described.

DESCRIPTION

FIG. 1 is a perspective view of an LED road flares arrow showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of the LED road flares arrow where the LED road flares arrow is in a configuration of use; and,

FIG. 10 is an enlarged view of portion 10 shown in FIG. 1. The broken lines in the drawings depict portions of the LED road flares arrow that form no part of the claimed design. The long-dash short-dash broken lines define the bounds of the claimed design and form no part thereof.
